UNITED STATES PATENT OFFICE.

HARRY TUNSTALL, OF FAIR HAVEN, MASSACHUSETTS, ASSIGNOR TO ALSATIAN MACHINE WORKS, LIMITED, OF BOSTON, MASSACHUSETTS, A CORPORATION OF MASSACHUSETTS.

COMBING MACHINE.

Application filed November 14, 1923. Serial No. 674,709.

To all whom it may concern:

Be it known that I, HARRY TUNSTALL, a subject of George V, King of England, and a resident of Fair Haven, in the county of 5 Bristol and State of Massachusetts, have invented a new and useful Improvement in Combing Machines, of which the following is a specification.

In United States Letters Patent No. 1,351-10 076, issued to me, and No. 1,416,951, issued to Joseph Fossel, there are described certain improvements on the well known Heilman comb. In my Letters Patent No. 1,351,076 there are shown top combs each having a 15 horizontal movement with means for moving it horizontally. I have found after considerable study that the top comb mounting and the adjustable means for operating the top comb may be simplified in various ways, 20 one of which is below described.

My invention will be understood by reference to the drawings in which it is shown in its preferred form as applied to a double-sided machine like that of my said patent.

25 Figure 1 is an elevation partly in section of so much of a double headed machine of the type shown in my said patent as relates to my present invention, this view corresponding somewhat to Fig. 3 of my said patent and showing also a portion of the machine of the said Fossel patent.

Fig. 2 is a plan thereof, the middle portion of one the heads being broken away, thus omitting the nipper frames, etc.

35 Fig. 3 is a side elevation of the driving end of the mechanism.

Fig. 4 is a detail showing the adjustment of the top comb moving link.

40 Fig. 5 is a detail taken at right angles to Fig. 4, showing also the top comb arm connection, and

Fig. 6 is a detail similar to Fig. 4, of the top comb adjustment.

45 In these views certain of the reference characters of the said patents are used so that the location of my present improvement on the original machine may be easily seen. In my said patent the top combs were operated from the crank disk 105 on shaft 8 and shafts 103. In the present case they are operated by the pendulum 12 which rocks the shaft 13 and for this purpose is forked as at 12^a and is connected to a crank disk 9 on shaft 8 by means substantially like 50 that shown in the said Fossel patent, so

that the pendulum 12 and the shaft 13 may be given a lateral swinging or oscillating movement which shall be equal in point of time and extent in each direction.

The Fossel arrangement for swinging the pendulum 12 comprises a carriage D having sleeves d running on rods C mounted in supports B on the frame A. Vertical ways D¹ mounted on said carriage carry a slidable block D² with a hole through it in which lies a crank pin 10. In a housing 9^a on crank disk 9 is mounted a block 10^a through which this crank pin 10 passes, and an adjusting screw 9^b passing through the outer wall of this housing adjusts the location of the block 70 and crank pin toward and from the axis of the crank disk 9 to adjust the swing of the pendulum. The forked end 12^a of the pendulum 12 straddles a block e¹ which is pivotally mounted in the carriage D so as to turn 75 slightly as required by the swinging movements of the pendulum. The rotation of the crank disk 9 causes the reciprocation of the carriage D and hence the swinging of the pendulum 12.

On the shaft 13 is mounted the plate 14 fast thereto, while the upper end of the pendulum 12 is loose on the shaft 13 and is adjustably held in place with relation to the shaft 13 and plate 14 by screws 15 which 85 pass through lugs in the plate 14 and engage the edges of the pendulum 12 which are shaped for the purpose as described in said patents.

The plate 14 is provided with a slot 141 90 and a bolt 121 projects through the slot 141 and carries a nut by which the plate and pendulum are securely fastened together when the proper adjustment has been made by the screws 15.

95 In describing the operations of the top comb it will be understood that in a double-sided machine as is shown in Fig. 1 the parts are duplicated on the two sides of the machine and are operated in turn (as are the nipper frames) by the pendulum as it swings first in one direction and then in the other. As the parts are identical, a description of the parts on one side only of a vertical line through the pendulum shaft 13 will 100 be necessary.

105 The pendulum shaft 13 carries a number of arms 36 each carrying a bowl 37 to operate the nipper frames as shown in Fig. 15 of my said patent. In my present invention 110

there are a series of bowls 37, as in my said patent. On each rockable shaft 29 are carried arms 32 in line to be struck by these bowls. To secure uniformity of action in 5 the case of a machine having a number of heads, there may be a number of arms 32 and 36 located along the machine, say one or more for each head.

To the bottom of each arm 32 is pivoted 10 a link 140 the outer end of which is pivotally secured to an arm 141 mounted loosely on the stub shaft 142. Fast on the shaft 142 is a collar 143 carrying a plate 144 having lugs 145 through which pass screws 146, 15 these screws being in line with the edge of the arm 141 so that as an arm 141 is caused to rock by the arm 32 and the link 140 the plate 144 will be moved because it is clamped to it by the screws 146, and will oscillate 20 to the shaft 142. The plate 144 is provided with a slot 147 and a bolt 148 passes through the arm 141 and the slot 147 to clamp the plate 144 and arm 141 together when their proper relation has been established in the 25 primary adjustment of the machine by the screws 146. In Fig. 1 these screws are shown in clamping position; in Fig. 4 the position of these screws is shown prior to the preliminary adjustment of the machine.

30 On the stub shaft 142 are also mounted arms 151, one at each side of the head. Between each pair of arms 151 a top comb carrier 152 is mounted, the top comb 48 being mounted between these carriers. 35 There is a slotted adjustable connection between the parts 151 and 152 to be used in the primary adjustment of the machine. It will be seen that the reciprocation of the links 140 will by this means cause the rocking of the shaft 142 and hence the reciprocation of the top comb carrier 152 and the top comb, and that as the rockable arms 141 are loose on the shafts 142, the throw of the top comb may be adjusted by adjusting 40 the position of the plates 144 about the shafts 142. The screw 149, which passes through the lug 150 (see Fig. 4), acts as a safety device to limit the movement of the system in case of any accident, for example, 45 the breakage of the spring 323 which is shown in my said patent as holding together the arms 32 thereof and which cooperates with the screws 321 and stop 642 to limit their swing. Where this mechanism is used 50 the breakage of the spring 323 which is shown in my said patent as holding together the arms 32 thereof and which cooperates with the screws 321 and stop 642 to limit their swing. 55 on a double-sided comb this arrangement is desirable because it utilizes but one spring to control the parts on both sides of the machine. If the mechanism is used on a single-sided comb one end of the spring 60 may be attached to the frame, the other end being attached to the arm 32.

The front end of each arm of the top comb carrier 152 overhangs the top comb and rests upon a roller 153 which supports them 65 so that they will move in a horizontal line.

The comb 48 is adjustably mounted at each end on an arm of the carrier 152. For this purpose it is attached to links 155, one at each end, which are pivoted to these arms at 154. The rear ends of these links are 70 adjustably connected, by a slot and bolt connection, to the arms. These parts are all so proportioned that as in my said patent the top comb will have a proper relation with the fluted rolls 83 and 84 as indicated in 75 Fig. 1, and in view of the minuteness of the fibre and the necessity for absolute accuracy in the arrangement and movements of the parts the various adjustments above described are found very desirable. Other 80 means of adjustably connecting the various parts may be adopted, if desired, but the above construction has been found in practice very satisfactory. Such adjustment is 85 desirable to control the amount of waste removed and for other purposes as will occur to those skilled in the art.

It will be seen from the foregoing description that my invention relates to a means of operating a top comb and it is so claimed. 90 While it is shown as applied to the double comb of my patent, it is operable equally well in a single-sided comb having means for rocking the shaft 29 or otherwise giving the proper movements to the parts referred to in the claims in connection with means for giving to the arms 32 the necessary swinging motion, which arms also operate the nipper mechanism as shown in my said 95 patent.

It will also be noted that as described in my said patent these arms 32, and hence both the nipper frames and the top combs, have in fact a dwell while in their rearward position, that is, they swing back until the screws 321 engage the stop 642, these screws and stops serving to adjust the rearward position of the nipper frames and in this case the top comb as well, while allowing the nipper frames and top comb on the other 105 side of the machine to perform their operations while the first-named nippers and top comb are stationary. The operation of the top comb therefore from the arm 32, which causes in this case the swinging of the nippers, gives to these two parts a coordination 110 in their movements which has been found extremely important.

What I claim as my invention is:—

1. In a machine of the kind described 120 having detaching rolls, a rockable shaft, a top comb frame and means for supporting said top comb frame whereby it may be moved horizontally, and connections between said rockable shaft and said frame comprising a rocker arm mounted on said rockable shaft and adjustable connections between said rocker arm and said frame whereby the throw of said frame may be adjusted and said frame will be given an intermittent re- 125 130

ciprocation towards and from said detach-
ing rolls.

2. In a machine of the kind described
having detaching rolls, a rockable shaft, a
5 horizontally-movable top comb frame and
connections between said shaft and said
frame whereby said frame will be moved
towards and from said detaching rolls, and
means for rocking said shaft comprising a
10 pendulum and means for swinging it and
adjustable connections between said frame
and said rockable shaft whereby the rocking
of said shaft and the forward throw of said
frame may be adjusted, and means for ad-
15 justably limiting the rearward throw of said
frame.
3. In a machine of the kind described, a
stub shaft and a top comb frame connected
thereto and means for giving said shaft an
20 oscillating movement whereby said frame
will be reciprocated comprising a swingable
arm fast on said shaft and means for swing-
ing said arm, an arm loosely mounted on
said shaft, a plate fast on said shaft, a link
25 connecting said swingable arm and said

loosely mounted arm, and means for adjust-
ing the relations of said loosely mounted
arm and said shaft.

4. In a machine of the kind described,
means for reciprocating the top comb frame
comprising a pendulum and means whereby
it may be oscillated, a top comb frame
adapted to be reciprocated, and connections
between said pendulum and said top comb
frame whereby the constant oscillation of
30 said pendulum will cause the intermittent
reciprocation of said top comb, said connec-
tions comprising a swingable arm adapted
to be moved by said pendulum as it swings
and a link connected to said arm to be moved
thereby, and connections between said link
35 and said top comb frame.

5. A combing machine having a swinging
arm adapted to operate the nipper frame
and means for operating said swinging arm
40 and a top comb mounted to move horizon-
tally and means connecting it to said swing-
ing arm whereby said nipper frame and said
top comb will be moved simultaneously.

LEONARD T. TROLAND.
